RATCHET MECHANISM

Edward M. Pfauser, Elm Grove, and Siegmund Mandl, Milwaukee, Wis., assignors to Blackhawk Mfg. Co., Milwaukee, Wis., a corporation of Wisconsin

Application May 6, 1948, Serial No. 25,354

3 Claims. (Cl. 192—43.2)

1

The present invention relates generally to improvements in ratchet assemblages, and relates more specifically to improvements in the construction and operation of reversible ratchet mechanisms especially adapted for use in imparting step-by-step rotation from an oscillatory handle to a tool or other machine element.

As shown and described in our prior Patent No. 1,995,009, granted March 19, 1935, we have heretofore provided a relatively compact and efficient reversible ratchet mechanism comprising a shank or lug adapted to be detachably but drivingly associated with a wrench socket or the like, a manipulating handle having a rigid head or body surrounding the lug and provided with an annular series of internal ratchet teeth, one or more spring pressed dogs slidably coacting with the lug and being reversibly cooperable with the teeth, and means for shifting the dogs to effect reversal of the operative engagement between the dogs and the ratchet teeth. While these prior ratchet assemblages were quite satisfactory and successful in operation, they were relatively complicated and difficult to manufacture with sufficient accuracy and strength in small sizes, and they were also rather awkward to reverse and to assemble and dismantle.

It is therefore a primary object of our present invention to provide improved ratchet mechanism of the same general type as that shown in our prior patent, but which obviates all of the above mentioned specific objections.

Another important object of this invention is to provide an improved ratchet assemblage which is composed of relatively few sturdy parts which may be readily assembled, manipulated during normal use, or dismantled for inspection.

A further important object of the invention is to provide an improved ratchet adapted to be durably and accurately constructed in large or small sizes, and wherein the various parts are amply protected against damage due to abuse.

Still another important object of our invention is to provide an improved reversible ratchet mechanism which may be conveniently manufactured in various sizes and for diverse uses at moderate cost, and which may be quickly and easily adjusted for reverse operation.

An additional object of the present invention is to provide a simple and compact ratchet assemblage all parts of which may be constructed in quantity so as to make them interchangeable with like parts and thus facilitating repairs resulting from prolonged use or abuse.

These and other objects and advantages of

2

the invention will be apparent from the following detailed description.

A clear conception of the several improved features and of a typical embodiment thereof in a ratchet assemblage, may be had by referring to the drawings accompanying and forming a part of this specification wherein like reference characters designate the same or similar parts in the various views.

10 Fig. 1 is a part-sectional side elevation of a typical ratchet mechanism especially adapted to impart step-by-step rotation in either direction from a manipulating handle to a wrench socket through a driving lug, the section having been taken centrally through the assemblage;

15 Fig. 2 is a fragmentary sectional view of the same mechanism, the section having been taken transversely through the assemblage along the line 2—2 of Fig. 1;

20 Fig. 3 is another fragmentary sectional view of the typical ratchet, the section having been taken transversely through the assemblage along the line 3—3 of Fig. 1;

25 Fig. 4 is still another fragmentary sectional view of the improved ratchet assembly showing the dogs in neutral or inactive position, and the section having been taken transversely along the line 4—4 of Fig. 1;

30 Fig. 5 is an additional fragmentary sectional view of the same ratchet mechanism, this section having been taken transversely through the lug along the line 5—5 of Fig. 1;

35 Fig. 6 is a side elevation of the improved driving lug alone and removed from the assemblage;

Fig. 7 is a front elevation of the improved power transmitting lug alone; and

40 Fig. 8 is an inside elevation of one of the improved ratchet dogs, removed from the mechanism, the view being taken in the direction of the arrows 8—8 of Fig. 1.

45 While we have shown and described the invention as being especially adapted for application to manually manipulatable wrench socket driving ratchet assemblages, it is not our intention to unnecessarily restrict the utility of the improved features by virtue of this limited disclosure; and it is also contemplated that specific description terms used herein be given the broadest possible interpretation.

50 Referring to the drawing, the improved reversible ratchet mechanism shown, comprises in general a unitary or one-piece shank member or lug 10 having parallel transverse guide recesses 11 therein on the opposite sides of its central axis; a manipulating member or handle 12 hav-

ing an integral head 13 surrounding the recessed portion of the lug 10 and provided with an annular series of internal teeth 14 revolvable about the head axis; a grip element or dog 15 slidable along each head recess 11 and being cooperable with the adjacent teeth 14; a composite longitudinally expansible toggle strut 16 coaxing with central semi-spherical sockets 17 formed in the two dogs 15; a shift plate 18 rotatably adjustable about the head axis and having integral lugs 19 coaxing with notches 20 formed in the adjacent ends of the dogs 15; and a button disc 21 slidably but non-rotatably mounted coaxially of the handle head 13, and having an annular series of serrations 22 cooperable with a similar series of serrations 23 formed on the shift plate 18.

The unitary lug member 10 is preferably constructed of a single cylindrical piece of durable metal having the parallel recesses 11 each bounded by four side surfaces and carefully milled in the opposite partially open sides thereof as best illustrated in Figs. 1, 4, 6 and 7; and this one-piece lug 10 has an integral wrench socket receiving shank 25 at one end, an integral outwardly projecting flange 26 near the shank 25 at one end of the recesses 11, and a pair of arcuate open slots 27 communicating with the opposite ends of the recesses 11, as clearly shown in Fig. 3. The lug 10 is also provided with a central transverse through opening 28 connecting the spaced recesses 11 and through which the toggle strut 16 extends, and moreover has an axial end depression 29 therein between the slots 27, while the shank 25 is provided with an ordinary spring pressed plunger 30 for effecting detachable frictional attachment of the wrench sockets or other tools thereto. The outer surface of the lug 10 adjacent to the recesses 11 is cylindrical and of such diameter that it will snugly fit but will revolve freely within the annular series of teeth 14, and all bearing surfaces of this lug are accurately machined and finished.

The manipulating handle member 12 besides having the annular internally toothed head 13 formed integral therewith, may be provided at its swinging end with a bore 31 for the reception of a rod handle extension, and with another spring pressed plunger 32 for effecting detachable frictional attachment of a tubular handle extension thereto. This handle 12 is also formed of durable metal and is bored to rotatably fit the lug flange 26 and the outer cylindrical surface of the lug 10 beyond the teeth 14; and the assembled lug 10 with the dogs 15 and toggle strut 16 applied thereto, may be inserted within the head bore and firmly but detachably confined therein by means of a special snap ring 33 coaxing with an annular internal groove 34 formed in the head 13, and having ring contracting eyes 35 at the opposite ends thereof, as depicted in Figs. 1 and 5. The handle head is also machined for sliding reception of the button disc 21, but does not coax with the shift plate 18 which is carried solely by the lug 10, and the annular internal teeth 14 should be accurately machined and equally spaced so as to provide a series completely surrounding the lug 10 at the zone of action of the dogs 15.

The two dogs 15 all four sides of each of which are slidably confined within each of the head recesses 11, are formed of wear resistant metal and are of interchangeably similar construction, being of elongated rectangular construction as shown in Fig. 8 in order to afford maximum

gripping action. These dogs 15 are constantly urged outwardly away from the central axis of the lug 10 and from each other, by the composite resilient strut 16 which, as shown in Figs. 1 and 4, is composed of a rod plunger 37 coaxing with the spherical socket 17 of one dog 15, a sleeve plunger 38 coaxing with the spherical socket 17 of the other dog 15 and telescoping over the rod plunger 37, and a compression spring 39 interposed between the telescopically coaxing plungers 37, 38. When the dogs 15 are in neutral or inactive position as in Figs. 3 and 4, the spring 39 will merely urge these dogs directly away from each other perpendicular to and directly against the outermost surfaces of the recesses 11, but if the dogs are shifted slightly in either direction away from neutral position, then the strut 16 expands and the spring 39 urges the displaced dogs along their respective confining recesses in opposite directions, until the dogs engage and are arrested by the adjacent teeth 14.

The shift plate 18 which is journalled for rotation in the end of the lug 10 remote from the flange 26, is ring-shaped, and the integral lugs 25 19 of this plate 18 extend from one side of this plate through the arcuate slots 27 of the lug and project well into the notches 20 of the adjacent dogs 15, as clearly illustrated in Figs. 1 and 3. The annular series of radial teeth or serrations 30 23 formed on the opposite side of the plate 18, are engageable with the serrations 22 formed on the button disc 21; and this disc is slideable in the head 13 toward and away from the plate 18 but is prevented from rotating relative to the 35 head 13 by a flat sided button projection 41 slidably engaging a similarly shaped hole formed in the unitary head 13. This button projection 41 is located centrally within a concavity 42 formed in the head 13 so as not to extend outwardly 40 beyond the latter, and the button disc 21 is constantly urged away from the shift plate 18 by a helical compression spring 43 one end of which is confined within the lug depression 29 and the opposite end of which is likewise confined within the button projection 41.

When the various parts of the improved ratchet mechanism have been accurately constructed as above described, they may be readily assembled by first inserting the button disc 21 and spring 43 50 within the head 13 through the open end of the latter; by thereafter assembling the lug 15, shift plate 18, strut 16, and dogs 15 and inserting this subassemblage within the head 13; and by finally applying the snap ring 33 to the internal groove 34 of the head 13. After the mechanism has been thus assembled, if the various parts are in the position shown in the drawings then the lug 10 may be rotated freely in either direction within the head 13 and the dogs 15 will be inactive. However, when the button projection 41 is pressed so as to cause the serrations 22 of the disc 21 to engage the serrations 23 of the shift plate 18, and the lug 10 is subsequently rotated relative to the head 13 by applying twisting motion to the shank 25, then the toggle strut 16 will become effective to shift the dogs 15 in opposite directions within their guiding recesses 11 and will throw these dogs into engagement with diametrically opposite teeth 14 of the annular series.

With the dogs 15 thus shifted, subsequent oscillation of the handle 12 will cause these dogs to be resolved step-by-step in one direction about the central axis of the head 13, thus producing step-by-step rotation of the shank 25 in the same pre-

selected direction. In order to reverse this predetermined direction of rotation of the lug 10, it is only necessary to reverse the direction of relative rotation of the head 13 and lug 10 while the button projection 41 is being pressed while shifting the dogs 15, but the oscillating motion of the handle 12 remains the same regardless of the setting of the plate 18 and dogs 15. The expandable toggle strut 16 will function to always shift and resiliently urge the dogs 15 in opposite directions within their respective guide recesses 11 when these dogs have been thrown in either direction out of neutral position, and the tooth engaging edges of the dogs 15 are so formed that they will drivingly engage the adjacent symmetrical V-shaped teeth 14 in only one direction of rotation and will ratchet over these teeth in the opposite direction.

From the foregoing detailed description of the construction and operation of the typical ratchet mechanism shown, it will be apparent that our present invention provides an improved reversible ratchet assemblage which besides being simple, compact, and durable in construction, is also highly efficient in operation and flexible in its adaptations. The unitary or one-piece construction of the lug 10 out of a solid piece of metal not only reduces the number of parts to a minimum, but also permits these mechanisms to be durably manufactured in small sizes and eliminates undesirable looseness in the dog guides. The one-piece formation of the handle 12 and head 13 with closed end also provides great strength while effectively protecting the working parts against possible damage due to rough handling of the tool, and the button projection 41 is protectively confined within the concavity 42 of the integral head end flange while the latter cooperates with the flange 26 and snap ring 33 to maintain the button disc 21 and the lug 10 in proper position within the head 13. By virtue of the sealed enclosure of all of the working parts of the improved ratchet mechanism, these parts may be maintained well lubricated and free from entry of dust and grit; and the smooth external surfaces of the enclosure besides improving the aesthetic appearance of the tool, also makes it possible to easily wipe these surfaces so as to keep them in clean condition. The snap ring 33 moreover facilitates assembly and dismantling of the parts without resorting to the use of special tools, while the positive reverse is easily operable, and the improved mechanism has proven highly satisfactory and successful in actual use.

It should be understood that it is not desired to limit this invention to the exact details of construction and operation of the typical ratchet mechanism, herein specifically shown and described, for various modifications within the scope of the appended claims may occur to persons skilled in the art.

We claim:

1. A ratchet mechanism comprising, a one-piece hollow head swingable about its central axis and having an annular series of integral internal teeth surrounding said axis, one end of said head being entirely open while its opposite end is provided with an integral inwardly directed flange forming a restricted central opening, a one-piece cylindrical lug journaled for rotation about said axis within said tooth series and having a work propelling shank remote from said flange projecting from said open head end, said one-piece lug also having therein a pair of parallel tangential recesses each having rectan-

gular cross-section bounded at all four corners by integral lug surfaces and said recesses being disposed within said tooth series on opposite sides of said axis and being connected by a medial passage, a dog slidably coacting with all of said four corner surfaces of each of said recesses, each dog being alternately engageable with said teeth through the opposite ends of its confining recess, a toggle strut extending through said medial passage and being swingable relative to said axis from one limiting radial position to another to urge said dogs in opposite directions, a shift plate confined between said head flange and said lug and being cooperable with said dogs, a single actuating button for said shift plate extending through said flange opening in axial alignment with said lug for swinging said strut from one limiting position to the other, and resilient means interposed between said lug and said button for constantly urging the latter into inactive position.

2. A ratchet mechanism comprising, a one-piece hollow head swingable about its central axis and having an annular series of integral internal teeth surrounding said axis, one end of said head being entirely open while its opposite end is provided with an integral inwardly directed flange forming a restricted central opening, a one-piece cylindrical lug journaled for rotation about said axis within said tooth series and having a work propelling shank remote from said flange projecting from said open head end, said one-piece lug also having therein a pair of parallel tangential recesses each having rectangular cross-section bounded at all four corners by integral lug surfaces and said recesses being disposed within said tooth series on opposite sides of said axis and being connected by a medial passage, a dog slidably coacting with all of said four corner surfaces of each of said recesses, each dog being alternately engageable with said teeth through the opposite ends of its confining recess, a toggle strut extending through said medial passage and being swingable relative to said axis from one limiting radial position to another to urge said dogs in opposite directions, a normally freely rotatable shift plate journaled in said head between said head flange and said lug and having dog engaging fingers on one side and serrations on its opposite side, and a single actuating button for said shift plate extending through said flange opening in axial alignment with said lug and having serrations cooperable with said plate serrations to swing said strut from one limiting position to the other.

3. A ratchet mechanism comprising, a one-piece hollow head swingable about its central axis and having an annular series of integral internal teeth surrounding said axis, one end of said head being entirely open while its opposite end is provided with an integral inwardly directed flange forming a restricted central opening surrounded by an external concavity, a one-piece cylindrical lug journaled for rotation about said axis within said tooth series and having a work propelling shank remote from said flange projecting from said open head end, said one-piece lug also having therein a pair of parallel tangential recesses each having rectangular cross-section bounded at all four corners by integral lug surfaces and the recesses being disposed within said tooth series on opposite sides of said axis and being connected by a medial passage, a dog slidably coacting with all of said four corner surfaces of each of said recesses, each dog being

alternately engageable with said teeth through the opposite ends of its confining recess, a toggle strut extending through said medial passage and being swingable relative to said axis from one limiting radial position to another to urge said dogs in opposite directions, a shift plate confined between said head flange and said lug and having dog engaging fingers on one side and serrations on the opposite side, and a single actuating button for said shift plate extending through said flange opening in axial alinement with said lug and having serrations cooperable with said plate serrations to swing said strut from one limiting position to the other, said button being constantly disposed within said concavity.
